UNITED STATES PATENT OFFICE.

JOHN L. NEBLE, OF OMAHA, NEBRASKA.

AUTOMATIC TRAIN-STOPPING SYSTEM.

1,091,694.

Specification of Letters Patent. Patented Mar. 31, 1914.

Application filed April 14, 1913. Serial No. 760,886.

To all whom it may concern:

Be it known that I, JOHN L. NEBLE, a citizen of the United States, residing at Omaha, in the county of Douglas and State 5 of Nebraska, have invented certain new and useful Improvements in Automatic Train-Stopping Systems, of which the following is a specification.

This invention relates to a system for 10 stopping trains which move on a single track, automatically, to prevent "head on" or "rear end" collisions, and consists of the novel construction, combination and arrangement of parts as described herein and 15 claimed, and as illustrated in the drawing, wherein,—

Figure 1 is a diagrammatic view showing part of a railway track. Fig. 2 is a broken, front view illustrative of a train provided 20 with devices for generating, conducting and applying electricity for stopping a train, the track, electrical contact-strips and car frame being in section. Fig. 3 is a rear view of the parts shown in Fig. 2. Fig. 4 25 is a diagram to illustrate the practical application of the system. Figs. 5, 6, 7, 8 and 9 are enlarged details of parts to clearly show electrical conducting devices. Figs. 5 and 6 are views of a contact-head or brush- 30 member, respectively, in longitudinal and transverse section. Fig. 7 is a broken view showing the contact-strips in transverse section and illustrating the use of cross-wires and their insulation for each of the blocks, 35 and a diagrammatic view of the wires arranged for the electromagnet and electric generator. Figs. 8 and 9, respectively, are side and end views of a contact-head or brush member, and it may be stated that, 40 while the brush-members for the electric generator and electromagnet are constructed the same in all respects, the numerals shown in connection with Fig. 8 indicate, for convenience, the electrical connection with the 45 electromagnet, while the indicating numerals applied to Fig. 5 describe electrical connections with the electric generator.

Referring now to the drawing for a more particular description, the track shown in 50 Fig. 1 may consist of suitable, separated sections or blocks of any desired length (a half-mile in length being practical), these blocks being indicated at 9, 9', 10, 10', 11, 11', 12, 12' and 13, and it will be understood that 55 trains may move in either direction upon all of the blocks of this single track.

Pivots mounted upon the frame of a car, as shown in Figs. 2 and 3, may be provided the pair of resiliently mounted arms or levers 16 for supporting, at their lower ends, the contact-heads or brush-members 17, and 17', and they are adapted to be disposed adjacent to strips 14 to make contact, respectively, with conductors *a*, *b*, *c* and *d*, and with conductors *a'*, *b'*, *c'*, and *d'*. 60

While I do not limit myself to detailed construction further than the scope of the appended claim, it may be stated that each contact-head or brush-member preferably consists of metallic disks or rollers 18, 19, 70 20 and 21 suitably insulated and mounted upon the pivot-pin 22, said pin also being insulated and having ball-bearings in the arms 23 of yoke 27, and the yokes may be suitably secured to arms or levers 16; and it 75 will be understood that the rollers or disks 18, 19, 20 and 21 of members 17 and 17' are adapted to make contact, respectively, with the series of conductors *a*, *b*, *c* and *d*, and with the series of conductors *a'*, *b'*, *c'* and 80 *d'*, these being supported by any suitable facing 30 of non-conducting material disposed on the contact-strips 14.

At 24, carried by each train, is indicated 85 an electric generator, having a conductor 25 leading to disks or rollers 18 and 20, and also provided with a conductor 26 in contact with disks 19 and 21, the medium of contact preferably being the metallic riders or 90 plugs *g* removably mounted in the insulating shield or housing 27' of the rollers, said conductor 25 being formed with branches *h* and *i*, and conductor 26 having branches *j* and *k*.

Carried by each train is an electromagnet 95 28, having a conductor 25' leading to disks 18 and 20 and provided with a conductor 26' in contact with disks 19 and 21 of brush-member 17', conductor 25' having branches *h'* and *i'*, and conductor 26' being provided 100 with branches *j'* and *k'* as shown in Figs. 7 and 8. When the wires or conductors leading thereto are energized, said electromagnet is adapted to cause a movement of lever 29; and any suitable arrangement of devices 105 (not shown) may be provided which may operate to communicate motion from this lever for applying the brakes, and to modify the driving force employed for moving a train and causing it to stop. The arrangement of the conductors and other devices on 110 all trains to be controlled by the herein de-

scribed system may be identical, and the rear view of parts shown in Fig. 3 is introduced to indicate a second train so that operation may be readily understood.

5 Operation will now be described showing that trains will be stopped automatically on the single track, if they approach each other and enter adjacent blocks, and this operation will be better understood by reference to Fig. 4, which is a diagrammatic view illustrative of the use of conductors *a*, *b*, *c*, and *d* upon strips 14 at one side of a track, in connection with the generator, and the use of conductors *a'*, *b'*, *c'* and *d'*, in connection with the electromagnet at the opposite side of the track.

To prevent a "head on" collision, it may be stated that if a train *m* is on block 11 and moving in the direction indicated by its arrow in Fig. 4, a train *n* coming upon the adjacent block 10' in the direction indicated by its arrow will be stopped automatically, since conductors *c'* and *d'* of one of strips 14 provide electric communication from the generator 24 of train *m* to the electromagnet 28 of train *n* for causing the latter to stop, and train *m* will likewise be stopped upon entering block 10' for the reason that the generator of train *n* will then energize the electromagnet 28 of train *m*, the medium being the wires *c* and *d*. Also a "rear end" collision will be prevented for the reason that if a train *p* comes upon block 11' while train *m* is upon block 11 its electromagnet 28 will be operated by the generator of train *m*, the medium of communication being conductors *a'*, *b'* through cross-conductors *e*, *f*, the conductors *a*, *b* and the conductors of the electromagnet of train *p*, to cause the latter to stop. Also it will be seen that if two trains are moving in the same direction, the electrical connection as described will not interfere with the movements of either of the trains unless the rearward train 45 enters a block adjacent to the block upon which the forward train is located.

It will be seen that a train moving in one direction, as for instance train *n* will energize the conductors *a*, *b*, *c*, *d*, and also 50 the conductors *a'* and *b'* in the block behind it. A train moving in the other direction, as either of trains *m* or *p*, will ener-

gize the conductors *a'*, *b'*, *c'*, *d'* as well as the conductors *a*, *b*, in the block behind it.

As described, the electromagnet and lever 55 29 provide actuating devices, which when operated may terminate the movement of the train on which they are disposed and these actuating devices upon two trains coming upon blocks adjacent to each other will 60 be operated automatically. Where trains approach each other, a "head on" collision will be prevented since both trains will stop if they come upon blocks adjacent to each other, and the system operates to advantage 65 where one train follows another since they may continue to move in the same direction unless they are upon adjacent blocks; and in that instance, the forward train may continue to move, and the rear train will automatically be detained until the forward train leaves the block on which it is temporarily located.

To prevent a "head on" collision, it may be stated that if a train *m* is on block 11 and moving in the direction indicated by its arrow in Fig. 4, a train *n* coming upon the adjacent block 10' in the direction indicated by its arrow will be stopped automatically, since conductors *c'* and *d'* of one of strips 14 provide electric communication from the generator 24 of train *m* to the electromagnet 28 of train *n* for causing the latter to stop, and train *m* will likewise be stopped upon entering block 10' for the reason that the generator of train *n* will then energize the electromagnet 28 of train *m*, the medium being the wires *c* and *d*. Also a "rear end" collision will be prevented for the reason that if a train *p* comes upon block 11' while train *m* is upon block 11 its electromagnet 28 will be operated by the generator of train *m*, the medium of communication being conductors *a'*, *b'* through cross-conductors *e*, *f*, the conductors *a*, *b* and the conductors of the electromagnet of train *p*, to cause the latter to stop. Also it will be seen that if two trains are moving in the same direction, the electrical connection as described will not interfere with the movements of either of the trains unless the rearward train 45 enters a block adjacent to the block upon which the forward train is located.

What I claim and desire to secure by Letters Patent is,

The herein described system for controlling the movements of trains on a single track, said system comprising a track arranged in blocks, two pairs of conductors arranged as a first series for each block, two pairs of conductors arranged as a second series for each block, one pair of conductors of the first series being connected to a corresponding pair in a rearward block, the other pair thereof being connected to a pair of conductors of the second series in a forward block, one pair of conductors of the second series being connected to a corresponding pair in a forward block, the other pair thereof being connected to a pair of conductors of the first series of a rearward block; a train having a source of energy contacts connecting said source across each of the pairs of conductors of one of said series, and having a train-controlling magnet and contacts connecting said magnet across each of the pairs of conductors of the other series.

In testimony whereof I have affixed my signature in presence of two witnesses.

JOHN L. NEBLE.
